UNITED STATES PATENT OFFICE.

JOHN W. ROGERS, OF FRENCHTOWN, NEW JERSEY.

RADIATOR FURNITURE.

Application filed January 14, 1928. Serial No. 246,662.

My invention relates to new and useful improvements in radiator furniture, such as is used in connection with hot water, steam or other similar radiators in buildings, particularly residences, and has for its primary object to provide an exceedingly simple and effective device of this character which may be placed over or about a radiator so that it may be used for supporting objects thus utilizing 10 space generally occupied by the radiator to an advantage.

Another object of the invention is to so construct the article of radiator furniture that the heated air will be deflected and the construction of the deflector is such that there can be no dead air pockets.

A further object of the invention is to provide a sliding top so that it can be moved to permit access to the radiator for cleaning 20 purposes and to the draining valves, and also permits the top to be moved back into contact with the adjacent wall so that any space between the furniture and wall will be closed at the top.

A still further object of the invention is to provide certain details of construction including the unique arrangement for producing the slideable top and the method and means of fastening the sides together and to 30 the deflector.

With these ends in view, this invention consists in the details of construction and combination of elements hereinafter set forth and then specifically designated by the 35 claims.

In order that those skilled in the art to which this invention appertains may understand how to use and make the same, I will describe its construction in detail, referring 40 by numerals to the accompanying drawings forming a part of this application, in which:—

Fig. 1, is a front elevation of the radiator furniture constructed in accordance with my invention, showing it placed over a radiator, only a section of which is shown and a portion of the deflector being broken away to clearly illustrate a detail of construction.

Fig. 2, is an end view thereof with a portion of the nearest end member broken away to show the cross brace in section.

Fig. 3, is an enlarged fragmentary sectional view at approximately the line 3—3 of Fig. 2.

Fig. 4, is an enlarged front edge view of one end of the sliding top, a portion of which

is shown in section together with one of the guide rails to illustrate the preferred method of connecting the parts.

Fig. 5, is also an enlarged front elevation 60 of the skeleton frame work with portions in section.

In carrying out my invention as herein embodied, 6 and 7 represent the end member or walls, each having a channel produced by a 65 router in its inner face adjacent the rear edge and including a straight portion 9 parallel with an edge of the end member and running the length thereof from the lower edge of the end member to a point adjacent the upper end 70 where said channel is curved forwardly as indicated at 10.

Within these channels are set the opposite edges of the deflector 11 of metal or other suitable material, the same being held in 75 place by a cross brace 12 running between the end members 6 and 7 and secured thereto by suitable fastening devices 13, such as screws, and by cleats 14 secured to the inner faces of the end members and to which the 80 deflector is attached by fastening devices 15 passing through said deflector into the cleats.

When the parts are so fastened the deflector is securely held in place without the use of frontal braces which tend to produce dead air 85 pockets in which dirt and dust often accumulate.

Along the upper ends or edges of the end members 6 and 7 are mounted guide rails 16 having their outer faces under cut or beveled 90 as at 17, and said guide rails are secured in place by suitable fastening devices such as screws 18 or their equivalent.

A top 19 for the furniture of desirable width is provided, it being understood that it 95 must be of such length as to project beyond the guide rails 17 when resting thereon and to the under surface of this top adjacent each end is fastened a companion guide rail 20 having its inner face under cut or beveled as 100 at 21 for coaction with a face 17 of a guide rail 16, thus permitting the top to slide back and forth while preventing it from being lifted from the end members. The companion guide rails are secured to the top by suitable fastening devices such as screws 22.

When the article of furniture is placed over a radiator, the apertures 23 in the lower edges of the end members register with the inlet or outlet pipe of the radiator and said 110 radiator is covered except for the front face and by moving or sliding the top toward the

adjacent wall, any space between the wall and the article of furniture is closed. Such an arrangement prevents articles from falling behind the furniture and in actual practice, the 5 top may be used for supporting useful or ornamental articles. The air passing about the radiator and being heated is deflected by the deflector 11 away from the wall or draperies and out into the room where its temperature 10 raising qualities are more readily felt. The particular construction of the deflector and its supporting elements eliminates all dead air pockets so that the heated air is passed out in a wave the width of the entire distance 15 between the end members.

Of course I do not wish to be limited to the exact details of construction as herein shown, as these may be varied within the limits of the appended claims without departing from 20 the spirit of my invention.

Having thus fully described my invention, what I claim as new and useful is:—

1. Radiator furniture comprising two end 25 members having longitudinal channels in their inner faces, the upper ends of said channel being curved inward, a deflector having its edges mounted in said channels, means to hold the deflector in said channels and a top slidably mounted on the upper ends of said 30 end members.

2. An article of furniture for use in connection with a heated radiator comprising end members having channels in their inner faces adjacent the rear edges, said channels

running parallel with said rear edges to 35 points adjacent the upper ends of said end members where the channels are curved toward the opposite edges of said end members, a deflector shaped to fit said channels and having its edges mounted therein, means to 40 hold said deflector and the associated end pieces together and a top slidably mounted on said end pieces.

3. An article of furniture for use with a heating radiator comprising side members 45 having channels in their inner faces adjacent the rear edges, said channels including straight lower portions and curved upper ends, a deflector having two opposite edges mounted in said channels, a cross brace se- 50 cured to the end members adjacent their upper ends to the rear of the deflector for holding the upper portions of said end members in proper spaced relation, cleats secured to the inner faces of said end members adjacent 55 their lower ends, means to secure the lower portion of the deflector to said cleats, guide rails having their outer side faces under cut mounted on top of the end members, a top 60 and companion guide rails carried by the under side of the top and having their inner faces under cut for coaction with the under cut faces of the first mentioned guide rails whereby said top is slidably mounted on said 65 end members.

In testimony whereof, I have hereunto affixed my signature:

JOHN W. ROGERS.
